US00D753700S

(12) United States Design Patent
Hiramatsu et al.

(10) Patent No.: US D753,700 S
(b4) Date of Patent: * Apr. 12, 2016

(54) DISPLAY PANEL OR SCREEN WITH
ANIMATED GRAPHICAL USER INTERFACE

(71) Applicant: Sony Computer Entertainment Inc.,
Tokyo (JP)

(72) Inventors: Shuji Hiramatsu, Tokyo (JP); Taku Sugawara, Tokyo (JP); Shinji Kimura, Los Angeles, CA (US)

(73) Assignee: Sony Computer Entertainment Inc.,
Tokyo (JP)

() Term: 14 Years

(21) Appl. No.: 29/464,845

(22) Filed: Aug. 21, 2013

(30) Foreign Application Priority Data

(57) CLAIM

The ornamental design for a display panel or screen with animated graphical user interface, as shown and described.

DESCRIPTION

FIG. 1 is a front view of a first image in a sequence of a display panel or screen with animated graphical user interface showing our new design; and,

FIG. 2 is a second image thereof.

The broken lines in the figures represent portions of the display panel or screen with animated graphical user interface that form no part of the claimed design.

1 Claim, 1 Drawing Sheet

FIG. 1

FIG. 2
